(57) **CLAIM**

The ornamental design for a cup lid, as shown and described.

DESCRIPTION

FIG. 1 is a front view of a cup lid, showing our new design; FIG. 2 is a rear view thereof; FIG. 3 is a left view thereof; FIG. 4 is a right view thereof; FIG. 5 is a top view thereof; FIG. 6 is a bottom view thereof; and, FIG. 7 is a perspective view thereof.

The evenly broken lines are shown for the purpose of illustrating parts of the article that form no part of the claim. The dot-dash broken lines represent the boundaries of the claim and form no part thereof.

1 Claim, 7 Drawing Sheets
